UNITED STATES PATENT OFFICE.

EDWIN SAVERY, OF SAN FRANCISCO, CALIFORNIA, ASSIGNOR TO BOESCH LAMP COMPANY, OF SAN FRANCISCO, CALIFORNIA, A CORPORATION OF CALIFORNIA.

SMOKER'S STAND.

Application filed May 17, 1923. Serial No. 639,493.

This invention relates to smokers' appliances and especially to a combined stand, match-box support, cigar tray and ash receptacle.

5 The object of the present invention is to generally improve and simplify the construction and operation of stands of the character described; to provide a self-righting stand comprising a combined base and refuse receptacle, a tube supported thereby, an ash tray in the upper end of the tube and in communication with the interior of the tube, a handle attached to the tray, and a match-box support carried by the handle; to 10 provide a tube which tapers or gradually increases in diameter from end to end to prevent pieces of paper, cigar stubs, etc., from lodging before the ash receptacle is reached, and further to provide a base which 15 may be readily disconnected from the tube to permit the receptacle formed therein to be readily emptied and cleaned. Other objects will hereinafter appear.

One form which my invention may assume is exemplified in the following description and illustrated in the accompanying drawings, in which—

Fig. 1 is a side elevation of the stand.

Fig. 2 is a central, vertical section.

30 Fig. 3 is a plan view of the stand.

Referring to the drawings in detail, and particularly to Fig. 2, A indicates in general a base member, the lower portion of which is filled with concrete 2 or a similar material. The base section serves three functions, first that of a support for the stand, secondly that of a receptacle for the weight 2, and third that of forming a receptacle or interior chamber 8 for the reception of 35 burnt matches, cigar stubs and like refuse.

The base proper consists of a bottom section 3, the lower portion of which is slightly flattened, as at 4, to permit the stand to normally assume a vertical upright position. The base is otherwise provided with an upper portion 7 and an intermediate bottom section 5, the weight 2 being disposed between the bottom sections 3 and 5. The bottom section 5 is convex in formation as 40 shown and thus presents a high central point 6 and sloping annular sides, this being of importance as it causes equal dis-

tribution of the refuse deposited in the receptacle. The upper end of the base is provided with a threaded annular sleeve 10 and this forms a connection between the tube indicated at 9 and the base, the tube being 55 interiorly threaded to form the threaded portion 10 and to permit the base to be readily detached so that it may be emptied, cleaned or otherwise. The tube supports 60 an ash tray 11 at its upper end, the ash tray being secured to the upper end of the tube in any suitable manner and being provided with a central opening 13 through which 65 ashes, burnt matches, cigar stubs, etc., are permitted to fall and pass through the tube 9 into the receptacle 8 formed in the base. The upper face or annular edge presented 70 by the ash tray is indented in two or more places to form a series of rests upon which may be deposited half-burnt cigars, cigarettes, etc. The ash tray is otherwise provided with an ornamental handle 14 by which the stand may be grasped and carried 75 from place to place, and the handle in turn is provided with a match-box support generally indicated at 15.

By referring to Fig. 1 and 2, it will be noted that the tube 9 tapers from end to end, 80 having its smallest diameter at the upper end, and its largest diameter at the lower end. This is of considerable importance as the increasing area presented prevents lodging of pieces of paper, matches, half-consumed cigar stubs, cigarettes, etc.; that is, 85 the increasing area permits anything entering the upper end of the tube to fully descend or to drop by gravity into the receptacle 8. The threaded connection indicated 90 at 10 is also of considerable importance as it permits ready detachment of the base when it is desired to empty and clean the same.

The weight 2 is another important feature, as is also the upwardly rounded sides of the bottom section 3. The weight normally retains the stand in a vertical position, while the rounded section 3 of the base permits rocking of the base to a considerable 100 angle without danger of upsetting. The annular flange indicated at 16, produced by interseaming the sections 3, 5 and 7, provides an annular stop which limits tilting move-

ment of the stand, thus preventing complete upsetting of the same if accidentally bumped or otherwise disturbed.

The stand as a whole is not only useful, but is ornamental in appearance, and as such can be employed both in hotels, public places and in the home.

While certain features of the present invention are more or less specifically illustrated, I wish it understood that various changes in form and proportion may be resorted to within the scope of the appended claims, similarly that the materials and finish of the several parts employed may be such as the experience and judgment of the manufacturer may dictate or various uses may demand.

Having thus described my invention, what I claim and desire to secure by Letters Patent is—

1. In a floor supported smoker's stand of the character described, the combination with an elongated hollow standard and a tray supported on the upper end thereof, of

a base member forming a support for the standard and the tray and a receptacle for smoker's refuse conveyed thereto through the tray and hollow standard, an exteriorly threaded flange on the base member forming an inlet to the receptacle and a connection between the standard and base whereby the standard and base may be disconnected to permit refuse in the base to be emptied out without clogging the threaded connection.

2. A floor supported smoker's stand of the floor type embodying in combination a hollow base constituting a receptacle, said receptacle having an inlet at its top, a standard connected to the base at the inlet thereof and having a conduit therein larger in diameter at its lower end than at the top to prevent lodgment of smoker's refuse and the like while being conveyed to the hollow base, and a tray carried by the upper end of the standard and having an opening formed therein in communication with the conduit in the standard.

EDWIN SAVERY.
